UNITED STATES PATENT OFFICE.

JOHN R. MITCHELL, OF CHICAGO, ILLINOIS, ASSIGNOR TO W. H. MINER COMPANY, OF CHICAGO, ILLINOIS, A CORPORATION OF ILLINOIS.

FRICITION SPRING DRAFT-RIGGING.

SPECIFICATION forming part of Letters Patent No. 782,409, dated February 14, 1905.

Application filed November 29, 1904. Serial No. 234,718.

To all whom it may concern:

Be it known that I, JOHN R. MITCHELL, a citizen of the United States, residing in Chicago, in the county of Cook and State of Illinois, have invented a new and useful Improvement 5 in Friction Spring Draft-Rigging, of which the following is a specification.

My invention relates to friction draft-rigging for railway-cars.

It consists in the novel construction of parts and devices and in the novel combinations of parts and devices herein shown or described.

In the accompanying drawings, forming a part of this specification, Figure 1 is a central vertical longitudinal section of a friction draft-rigging embodying my invention. Fig. 2 is a plan view, partly in horizontal section. Fig. 3 is a cross-section on line 3 3 of Fig. 2, and Fig. 4 is detail perspective view of the 20 vertically-movable friction-block.

In the drawings, A A represent the center sills or draft-sills of a car.

A' is the front or cross sill; A², the buffer-plate; A³, the rear face-plate of the front or 25 cross sill, and A⁴ the carry-iron.

B is the car-coupler; B', the draw-bar; D, the friction draft-iron, and C a strap or yoke secured to the draw-bar by bolts or rivets c and connecting the draft-iron to the draw- 30 bar, said strap or yoke extending through the vertical slot or eye d in the draft-iron and embracing the rounded head d' of the draft-iron. The draft-iron D has a straight friction-face d² on its lower side having frictional engagement with a stationary friction- 35 plate E, which is rigidly but removably secured to the side plates G of the draft-rigging. The draft-iron D has oppositely-disposed inclined friction-faces d³ d⁴, which frictionally 40 engage the corresponding inclined friction-faces f of the transversely or vertically movable block F.

H is a transversely-arranged spring acting against the transversely - movable friction- 45 block F.

The side plates G G are cast integral in one piece and are provided with laterally-projecting arms G', having each a horizontal flange g, fitting under the lower face or flange a of

the draft-sills and secured thereto by rivets 50 a'. The outwardly-projecting arms G' are also furnished with upright flanges or webs g', which fit against the upright faces or webs a² of the draft-sills A and secured thereto by rivets a'. The side plates G are further provided with integral outwardly-projecting flanges g² at their lower edges, through which short or stub bolts E' extend to secure the stationary friction-plate E in place. The stationary friction-plate E not only serves as a 55 friction device to resist longitudinal movement of the draw-bar, but also to support the draft-rigging and friction device between the side plates G G. The side plates G G are connected integrally together by an integral 60 cap or member G², having a cavity or recess G³ to receive the spring H and form a bearing for the upper end of the spring. This integral cap G² is also provided with an integral downwardly-projecting stem or stud g³ 65 to center the small spring h, which is nested within the larger spring H.

The transversely or vertically movable friction-block F is provided with upright guide faces or shoulders f², preferably four in number, on each side of the block, engaging corresponding guide faces or shoulders g⁴ on the side plates G. The friction-block F is further provided at its upper end with a cavity or recess F' to receive the lower ends of the 70 springs and also with an integral stud f³ to center the springs.

By this construction my friction draft-rigging is made very simple in form and compact and adapted to be located directly between the center sills, thus affording a secure anchorage.

The side plates G G have at their ends integral flanges g⁵, secured by bolts g⁶ to the front sill of the car-frame.

I claim—

1. In a friction draft-rigging, the combination with the draft-sills and draw-bar, and a friction draft-iron having a lower friction-face in sliding frictional engagement with a stationary friction-plate and oppositely-disposed inclined friction-faces on its upper side, of a vertically-movable friction-block having op-

- positely-disposed inclined friction-faces engaging friction-faces on the draft-iron, a stationary removable friction-plate, a transversely-arranged spring bearing against said friction-block, and side plates having an integral connecting-cap furnished with a recess to receive the upper end of the spring, and provided with outwardly-projecting arms having horizontal and upright flanges fitting against and secured to the draft-sills, substantially as specified.
2. In a friction draft-rigging, the combination with the draft-sills and draw-bar, and a friction draft-iron having a lower friction-face in sliding frictional engagement with a stationary friction-plate and oppositely-disposed inclined friction-faces on its upper side, of a vertically-movable friction-block having oppositely-disposed inclined friction-faces engaging friction-faces on the draft-iron, a stationary removable friction-plate, a transversely-arranged spring bearing against said friction-block, and side plates having an integral connecting-cap furnished with a recess to receive the upper end of the spring, and provided with outwardly-projecting arms having horizontal and upright flanges fitting against and secured to the draft-sills, said integral cap of said side plates and said friction-block having each an integral stud for centering the springs, substantially as specified.
3. In a friction draft-rigging, the combination with the draft-sills and draw-bar, and a friction draft-iron having a lower friction-face in sliding frictional engagement with a stationary friction-plate and oppositely-disposed inclined friction-faces on its upper side, of a vertically-movable friction-block having oppositely-disposed inclined friction-faces engaging friction-faces on the draft-iron, a stationary removable friction-plate, a transversely-arranged spring bearing against said friction-block, and side plates having an integral connecting-cap furnished with a recess to receive the upper end of the spring, and provided with outwardly-projecting arms having horizontal and upright flanges fitting against and secured to the draft-sills, said side plates and vertically-movable friction-block having a plurality of interengaging upright guide faces or shoulders, substantially as specified.

guide faces or shoulders, said friction-block having a recess or cavity to receive the lower end of said spring, substantially as specified.

4. In a friction draft-rigging, the combination with the draft-sills and draw-bar, and a friction draft-iron having a lower friction-face in sliding frictional engagement with a stationary friction-plate and oppositely-disposed inclined friction-faces on its upper side, of a vertically-movable friction-block having oppositely-disposed inclined friction-faces engaging friction-faces on the draft-iron, a stationary removable friction-plate, a transversely-arranged spring bearing against said friction-block, and side plates having an integral connecting-cap furnished with a recess to receive the upper end of the spring, and provided with outwardly-projecting arms having horizontal and upright flanges fitting against and secured to the draft-sills, substantially as specified.

5. In a friction draft-rigging, the combination with the draft-sills and draw-bar, and a friction draft-iron having a lower friction-face in sliding frictional engagement with a stationary friction-plate and oppositely-disposed inclined friction-faces on its upper side, of a vertically-movable friction-block having oppositely-disposed inclined friction-faces engaging friction-faces on the draft-iron, a stationary removable friction-plate, a transversely-arranged spring bearing against said friction-block, and side plates having an integral connecting-cap furnished with a recess to receive the upper end of the spring, and provided with outwardly-projecting arms having horizontal and upright flanges fitting against and secured to the draft-sills, said integral cap of said side plates and said friction-block having each an integral stud for centering the springs, substantially as specified.
